UNITED STATES PATENT OFFICE.

CYPRIEN GOUSSET, OF NEW YORK, N. Y.

CHOCOLATE-DIPPER.

SPECIFICATION forming part of Letters Patent No. 552,833, dated January 7, 1896.

Application filed November 21, 1894. Serial No. 529,433. (No model.)

To all whom it may concern:

Be it known that I, CYPRIEN GOUSSET, of New York city, in the county and State of New York, have invented a new and Improved Chocolate-Dipper, of which the following is a full, clear, and exact description.

My invention relates to improvements in that class of devices which are used for dipping cream-drops into a chocolate solution and which may be used for dipping candies of various sorts. Such dippers have usually a series of open-sided and open-topped pockets, and it is necessary to cover each pocket to prevent the drops or candies from being displaced during the dipping process, and it is also necessary to have the cover of an open structure, so that the solution will not be prevented from completely coating the articles dipped.

The object of my invention is to produce a cover for chocolate-dippers which subserves the above ends, and which is very cheap and simple in construction, easily applied to the dipper, which offers but little surface for the accumulation of solidified chocolate, and which may be instantly operated to open or close the pockets.

To these ends my invention consists of certain features of construction and combinations of parts, which will be hereinafter described and claimed.

Reference is to be had to the accompanying drawings, forming a part of this specification, in which similar figures of reference indicate corresponding parts in all the views.

Figure 1 is a broken plan view of a dipper provided with my improved cover. Fig. 2 is a longitudinal section on the line 2 2 of Fig. 1. Fig. 3 is an enlarged detail sectional view on the line 3 3 of Fig. 4, showing more clearly the construction of the several parts; and Fig. 4 is a broken sectional plan on the line 4 4 of Fig. 3.

The chocolate-dipper has a suitable skeleton frame 10, which may be of any approved construction and which should have legs 11 on which it may stand. The frame has also suitable end bails 12 and is provided with a series of open-topped and open-sided pockets 13, formed by intersecting and longitudinal cross-wires; but the construction of the frame

and pockets is not shown or described with great detail, because such construction forms no part of this invention and the pockets may be formed and supported in any suitable manner, and the pockets, instead of being shaped to hold cream-drops, as illustrated, may be elongated to hold candy sticks or may be given any desired shape.

At the ends of the dipper and opposite the bails 12 are inverted-U-shaped levers 15, which are preferably bent outward in the center, as shown at 16, in order that they may be more conveniently grasped and operated, and the legs of these levers are provided with clips 17, which are pivoted to clips 18 on the sides of the bails 12, although the U-shaped levers 15 may be pivoted or fulcrumed in any other suitable manner without affecting the principle of the invention. These levers are at their lower ends secured, as shown at 19, to cross-bars 20, and each cross-bar has secured to it an independent set of parallel bars 21, which extend the full length of the dipper and over the center of the pockets 13, the bars being held to slide in keepers 22 on cross-bars 14, which are secured to the frame 10 and assist in supporting the pockets 13, while the ends of the strips or bars 21 are, at the end of the dipper opposite the lever to which they are attached, connected by a cross-bar 23. There are two sets of these sliding cross-bars or strips 21, one set being worked by one lever 15 and secured to one rod or cross-bar 20, while the other set of strips or bars are connected in a similar way to the opposite lever 15, and the strips or bars of one lever are alternated with those of the other, so that when the two levers 15 are moved the strips or bars 21 are all moved together, but one set moves in a direction opposite to that in which the other moves.

The slide bars or strips 21 are provided with cross-arms 24, preferably formed of wire loops in order that they may be as open as possible, so as not to hold too much solution, and when the upper ends of the levers 15 are thrown outward the arms 24 are all moved so as to align with points between the several series of pockets; but when the tops of the levers are moved inward toward the bails 12 the arms are brought exactly over the pock-

ets 13 and thus prevent the cream-drops 25 (see Fig. 1) from being forced out of the pockets during the dipping process.

When the dipper is used, the levers 15 are tipped outward, as in Fig. 1, the several pockets filled with the drops 25 to be dipped, and then to operate the dipper it is only necessary to lift it and dip it in the usual manner, as by grasping the bails 12. The levers 15 may be simultaneously grasped, and these levers are naturally squeezed toward the bails 12, and thus work the strips or bars 21 so as to bring the retaining-arms 24 above the cream-drops.

Having thus described my invention, I claim as new and desire to secure by Letters Patent—

1. The combination of a chocolate dipper, having a series of pockets and a cover connected thereto and adapted to be moved parallel to the upper face thereof, said cover having arms adapted when the cover is moved, to close the mouths of the pockets, substantially as set forth.

2. The combination, with a chocolate dipper having a series of pockets, of a cover comprising a series of slide bars, and laterally extending retaining arms, substantially as described.

3. The combination, with a chocolate dipper having a series of pockets, of a series of slide bars held to move in keepers on the chocolate dipper, and laterally extending retaining arms to project over the pockets, substantially as described.

4. The combination, with the chocolate dipper having a series of pockets, of the slide bars held to move longitudinally on the dipper and connected at the ends by cross bars,

laterally extending retaining arms on the slide bars, and a lever mechanism to move the bars, substantially as described.

5. The combination, with the chocolate dipper having a series of pockets, of the slide bars movable on the dipper, the cross bars connecting the slide bars, the retaining arms projecting from the slide bars, and a tilting lever at the end of the dipper to move the slide bars, substantially as described.

6. The combination, with the chocolate dipper having a series of pockets and end bails, of the connected slide bars on the top of the dipper, the retaining arms on the slide bars, and the U-shaped lever fulcrumed on the bails and connected with the slide bars, substantially as described.

7. The combination, with the chocolate dipper having a series of pockets and end bails, of the U-shaped levers opposite the bails and fulcrumed thereon, the double series of slide bars connected with the levers and movable above the pockets, and the retaining arms on the slide bars, substantially as described.

8. The combination of a chocolate dipper, having a series of pockets and a cover mounted on said dipper and provided with arms located to correspond with the mouths of the pockets, said arms being separated by spaces adapted for the passage of candies, said cover being adapted for movement parallel to the upper face of the dipper whereby the mouths of the pockets may be opened and closed, substantially as set forth.

CYPRIEN GOUSSET.
